UNITED STATES PATENT OFFICE.

OLAF E. FELLAND, OF BLOOMER, WISCONSIN.

BENCH-DOG.

1,357,970.

Specification of Letters Patent.

Patented Nov. 9, 1920.

Application filed August 2, 1920. Serial No. 400,739.

To all whom it may concern:

Be it known that I, OLAF E. FELLAND, a citizen of the United States, residing at Bloomer, in the county of Chippewa and 5 State of Wisconsin, have invented a new and useful Bench-Dog, of which the following is a specification.

This invention relates to work benches employed in wood working, and more particularly to bench dogs forming a part of 10 the bench, it being the primary object of the invention to provide a bench dog which may be adjusted vertically and longitudinally of its support at the will of the operator, thereby adapting the dogs for use with 15 material of various sizes.

A further object of the invention is to provide an automatic locking means for locking the elements of the bench dog, in 20 their various positions of adjustment.

A still further object of the invention is the provision of a bench dog which will firmly grip the material under operation, when pressure is applied thereto, during the 25 planing.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without departing from the spirit of the invention. 35

Referring to the drawing:—

Figure 1 illustrates a fragment of a bench, showing the invention as applied thereto. 40 Fig. 2 illustrates a sectional view taken on line 2—2 of Fig. 1.

Fig. 3 illustrates a sectional view taken on line 3—3 of Fig. 2, and

Fig. 4 illustrates a modified form of locking means employed in connection with the bench dog.

Referring to the drawing in detail, the reference character 5 designates a portion of a bench, which is cut away to receive the 50 base or supporting member of the bench dog.

This base includes an upper stationary member 6, which is relatively long and provided with a plurality of openings 7 extending therethrough, the upper member 55 having a right angled end portion 8, which is also apertured to receive the securing screws 9 which pass into the bench proper to secure one end of the base to the bench, the opposite end of the member 6 being secured to the bench as by means of the screws 10.

Associated with the stationary member 6 is a movable member indicated at 12, which movable member is also relatively long and 65 provided with a plurality of openings indicated at 13, which openings are slightly larger than the openings 7, each of which being provided with an offset portion indicated at 14, the openings in the stationary 70 member and movable member being designed to register with each other for purposes to be hereinafter more fully described.

In order that the movable member will be retained in operative relation with the 75 stationary member, transversely extending supporting bars 15 are provided which have their ends secured to the stationary member 6, the central portions thereof being offset to accommodate the lower movable member 80 so that the lower movable member may slide longitudinally of the upper stationary member.

One of the bars 15 is provided with a hooked portion as at 16, which hooked portion provides a retaining member for one extremity of the coiled spring 17, the opposite extremity of said coiled spring being positioned over the hooked member 18 so that a pressure will be exerted on the 90 movable member 12 to normally hold the openings 7 and 13 out of registry with each other.

The clamping members of the dog include a pair of arms 18' which have their 95 ends oppositely curved, there being a central rod 19 having connection with each of the arms, which rods are provided with a plurality of cut out portions 20 disposed in spaced relation throughout the lengths 100 thereof to provide shoulders 21, and inclined surfaces 22, the inclined surfaces be-

ing designed to ride over one wall of the non-registering openings to move the movable member 12 longitudinally of the stationary member 6, with the result that the 5 coiled spring 17 urges the movable member 12 in the opposite direction to cause the walls of the openings to frictionally engage the rod 19 associated therewith.

It will of course be understood that when 10 a bench dog constructed in accordance with the present invention is applied to a bench, openings indicated at 23 should be formed in the bench to register with the openings 7 of the stationary plates 6, so that the rods 15 of the clamping members of the bench dog may pass through the openings of the bench and be secured in upright positions.

If it is found desirable to employ this 20 bench dog for use with a board, in the event that a work bench is not available, openings corresponding to the openings 23 may be formed in a board, and the clamping member illustrated more particularly by Fig. 4 of the drawing, may be secured to the 25 supporting rods of the clamping members, to support the same in upright positions.

These clamping members comprise a pair of opposed jaws 24 pivotally connected as at 25, a coiled spring 26 being shown as 30 having connection with each of the jaws 24, to normally urge the same toward each other so that when the clamping member is positioned on a rod, the same will firmly grip the rod.

35 From the foregoing it is obvious that if a relatively thick board is to be planed, the clamping members may be moved to a position in greater spaced relation with the upper surface of the bench, than that shown 40 by Fig. 2 of the drawing, by merely forcing the movable member inwardly, to cause the openings of the stationary member and movable member to aline, whereupon the clamping members may move vertically to 45 a predetermined position. It follows that upon releasing the movable member 12, the spring 17 forces the movable member in one direction, causing the openings in the stationary and movable members to be moved 50 out of alinement to clamp the supporting rods of the clamping member.

If a relatively wide board is to be operated on, it is only necessary to move the supporting rods or clamping members to predetermined openings in greater spaced relation with each other, or in positions to accommodate a particular board.

Having thus described the invention, what is claimed as new is:—

60 1. In a bench dog, a stationary member and a movable member, each of said members having a plurality of openings disposed in spaced relation with each other, throughout the lengths thereof, clamping members 65 forming a part of the bench dog, each of said

clamping members having a supporting rod adapted to be positioned in the openings, and means for moving the movable member with relation to the stationary plate to cause the walls of the openings of the movable 70 plate to frictionally engage the supporting rods.

2. In a bench dog, a stationary member and a movable member, each of said members having openings formed therein, clamping members including arms having oppositely curved extremities, a supporting rod having connection with each arm, and having a plurality of notches formed therein, means for normally holding the openings 80 of the movable member out of alinement with the openings of the stationary member, and clamping members adapted to be clamped by frictional engagement of the walls of the openings of the movable 85 member.

3. In a bench dog, a stationary member and a movable member, means for connecting the members to permit movement of the movable member longitudinally of the stationary member, each of said members having openings formed therein, means for normally urging the openings out of alinement 90 with each other, and clamping members disposed within the openings, and adapted to 95 be clamped by the frictional engagement of the walls of the openings of the movable member.

4. In a bench dog, a stationary member and a movable member, each of said members having openings formed throughout the lengths thereof, said openings adapted to aline, means for normally urging the openings out of alinement, clamping members, each of the clamping members including a supporting rod having notches formed therein, said supporting rods adapted to be disposed in predetermined openings, and the walls of the openings of the movable member in which the rods are disposed, adapted 110 to clamp the rods against movement, by their frictional contact therewith.

5. In a bench dog, a stationary member and a movable member, said members having openings, a coiled spring having connection with each of the members for normally urging the openings out of alinement with each other, clamping members, each of said clamping members having an arm adapted to overlie the stationary member 120 and movable member, and means forming a part of each arm and disposed in predetermined openings for supporting the clamping members in spaced relation with the stationary member.

125 6. In combination with a bench having openings formed therein, a bench dog including a stationary member and a movable member, each of said members having openings alining with the openings of the bench,

means for normally urging the openings of the members out of alinement with each other, and clamping members disposed in the openings for supporting the clamping members with relation to the supporting members.

In testimony that I claim the foregoing

as my own, I have hereto affixed my signature in the presence of two witnesses.

OLAF E. FELLAND.
